UNITED STATES PATENT OFFICE.

JOHN J. SULLIVAN, OF IPSWICH, MASSACHUSETTS, AND ALBERT F. FIFIELD, OF BRIDGEPORT, CONNECTICUT, ASSIGNORS TO THE SINGER MANUFACTURING COMPANY, A CORPORATION OF NEW JERSEY.

THREAD-CUTTING MECHANISM.

1,151,735.

Specification of Letters Patent. Patented Aug. 31, 1915.

Application filed November 14, 1912. Serial No. 731,242.

To all whom it may concern:

Be it known that we, JOHN J. SULLIVAN and ALBERT F. FIFIELD, citizens of the United States, residing, respectively, at Ipswich, in the county of Essex and State of Massachusetts, and Bridgeport, in the county of Fairfield and State of Connecticut, have invented certain new and useful Improvements in Thread-Cutting Mechanisms, of which the following is a specification, reference being had therein to the accompanying drawings.

While the present invention is adapted for application to various types of sewing machines, it is especially designed for embodiment in button sewing machines of the type shown in the United States patent to J. J. Sullivan and E. B. Allen No. 742,366, of October 27, 1903, and it has for one of its chief objects to simplify and to render more effective the class of thread-cutting mechanism to which said patent is directed.

Certain other objects will appear in connection with the following description.

As preferably constructed, the cutting device is composed of overlapping thread-cutting and -nipping blades slidably mounted within a transverse guideway of the presser-foot and whose extremity at the needle aperture affords shoulders co-operating with the operative edges of such blades in the nipping and severing actions upon the needle-thread. Mounted upon a fixed fulcrum of the machine is a plural-armed lever having one arm connected by a link with the cutting and nipping blades and another arm operatively connected with the controlling cam for imparting lateral jogging movements to the needle and controlling the period of action of the stitch-forming mechanism through the usual stop-motion device. By means of the controlling cam operative movements are imparted to said lever for retracting the blades from nipping and cutting or operative position into a position at the opposite side of the needle-path in readiness for a succeeding nipping and cutting action; and after the thread leading from the final stitch of a group has been loosely embraced by the blades, the action of automatic presser-foot lifting means thereon through a connection with a third arm of the plural-armed lever imparts to the nipping and cutting blades a quick operative

movement while the needle is raised for nipping and cutting the thread.

The nipping blade is preferably provided in its operative or nipping face with one or more indentations into which the thread is compressed between such face and the adjacent face of the guide-channel so as to form protruding parts of the partially crushed thread which lock the same in position in addition to the frictional action of the parts between which it is thus clamped.

In the drawings, Figure 1 is a rear side elevation of a Singer button sewer embodying the present improvements, and Fig. 2 a front end view of the same. Fig. 3 is a perspective view of a portion of the stop-motion device, showing the operative connection between the same and the presser-foot lifting mechanism. Fig. 4 is a side elevation of the cutting mechanism and certain parts connected therewith, and Fig. 5 an end elevation of a portion of the cutter-actuating mechanism. Fig. 6 is a perspective view of the presser-foot and the cutting elements positioned therein for a cutting action. Fig. 7 is an enlarged sectional elevation showing the action of the cutting device upon the thread. Figs. 8 and 9 are perspective views of the overlapping cutting and nipping blades taken respectively from the upper and lower sides.

As represented herein, the frame of the machine comprises a hollow standard 1 with laterally extending work-supporting arm 2 and overhanging bracket-arm 3 in which is journaled the main-shaft 4 having upon its rear end the loose belt-pulley 5 and fast pulley 6 to which is attached the stopping cam 7 formed with the eccentric periphery 8 terminating in the notch 9. The head of the bracket-arm has mounted therein the laterally jogging needle-bar frame 10 and in which is journaled the needle-bar 11 carrying the needle 12 and connected by means of the pitman 13 with the crank-stud 14 upon the take-up cam-cylinder 15 secured upon the main-shaft 4 and from which the needle derives its reciprocating movements. The needle-bar frame is connected by means of the pitman 16 and other connections with the suitably grooved controlling cam 17 which imparts lateral jogging movements to the needle for production of fastening over-seam stitches.

Within a suitable race 18 applied to the work-supporting arm 2 is mounted the shuttle 19 coöperating with the reciprocating and laterally jogging needle 12 and provided 5 with the usual bobbin-case 20 for the lower thread.

Mounted within the head of the bracket-arm is the usual presser-bar 21 normally pressed downwardly by means of a spring 22 10 interposed between the lower end of the bushing 23 and the collar 24 fixed thereon and provided with the lateral lug 25 and with a second forked lug 26 embracing the guide-pin 27. Secured by means of the 15 fastening screw 28 upon the lower end of the presser-bar is the shank 29 of the presser-foot 30 formed in its forward portion with the needle-slot or aperture 31 and at one side thereof with the lateral extension 32 which 20 is shown provided in its lower face with the transverse guide-channel 33 closed in its lower side by means of the plate 34 secured thereto by screws 35. The presser-foot is 25 shown cut away rearward of the needle-aperture 31 to form the transverse button-guiding seat 36.

Mounted within the guide-channel or guideway 33 is a compound cutting and nipping element comprising two overlapping 30 blades 37 and 38 which are normally reversely arched, as represented in Figs. 8 and 9 and formed at the rearward end with alined apertures 39. At the opposite ends, 35 these blades are provided with lateral hooked extensions 40 and 41 having operative shoulders 40' and 41' upon the inner edges of the faces farthest apart. In practice, the edge 40' of the nipping member 40, which is arranged slightly in advance of the edge 41', 40 is slightly rounded so as to avoid injuring the thread nipped between the same and the correspondingly formed operative shoulder 32' of the channel 33, while the edge 41' is sharpened, as represented in Fig. 7, so as 45 to produce a shear-cut in conjunction with the opposed shoulder 34' of the channel 33. The nipping element 40 is shown provided in its upper or outer face with the nicks or indentations 42 into which a portion of the 50 needle-thread *n* is compressed, in the nipping operation, as represented in Fig. 7, to insure against pulling out of the cut end of thread leading to the needle in the production of the initial stitch of a group succeeding 55 in a nipping and cutting action.

The rearward ends of the blades 37 and 38 are secured by means of the clamp-screw 43 within a depressed seat formed therefor in the block 44 which is provided with the 60 spaced and apertured ears 45 between which is pivotally secured by means of the screw-pin 46 one end of a link 47 whose apertured opposite end is connected by means of the screw-pin 48 with the depending arm 49 of an angle-lever having a hub 50 and a lat-

eral arm 51 carrying the roller-stud 52. The hub 50 of the angle-lever 49 51 is secured by means of the set-screw 53 upon one end of the rocking pin 54 journaled in the bearing boss 55 of the bracket-arm 3 and having 70 secured upon its opposite end by means of the set-screw 56 the hub 57 of an upwardly extending arm 58 carrying a roller-stud 59 which enters the cam-groove 60 of the controlling cam 17. The members 49 51 and 58 75 being rigidly connected together, constitute a plural-armed lever fulcrumed upon the bearing boss 55.

Mounted upon the fulcrum-stud 61 sustained by the bracket-arm 3 is the presser-foot lifting rock-lever comprising the forwardly extending arm 62 projecting beneath the lug 25 of the presser-bar collar 24 and the rearwardly extending arm 63 carrying the lateral stud-pin 64 which is embraced 85 by the forked forward end 65 of the arm 66 of a rock-lever mounted upon the fixed fulcrum-stud 67 and having the rearwardly extending arm 68 provided with the laterally offset perforated boss 69. The boss 69 has 90 fitted within its socket the plunger-pin 70 whose reduced rearward end is provided with the thrust-nut 71 and jam-nut 72 to sustain the thrust of the spring 73 encircling the same and interposed between the inner end of the socket and the enlarged forward end of the pin.

The plunger-pin 70 is adapted to engage the top and adjacent inclined side of the collar 74 fixed upon the plunger-bar 75 100 which is journaled in the rocking stop-lever 76 fulcrumed at 77 upon the bracket 78 sustained by the standard 1. Interposed between the bearing boss 76' of the lever 76 and the collar 74 is a spring 79 which forces the upper end of the plunger-bar 75 into operative relation with the periphery of the stopping cam 7. The plunger-bar is normally maintained in operative relation with the stopping cam by means of a spring 80 110 interposed between the upper portion of the stop-lever 76 and the standard 1, and is shifted laterally in opposition to such spring for disengagement of the plunger-bar and stopping cam by means of a lateral arm 81 115 of the stop-lever whose apertured outer end is entered by the headed upper extremity of the treadle-rod 82.

The arm 81 carries a laterally projecting stud 83 embraced by the forked extremity 84 120 of the lateral arm 85 of an angle-lever mounted upon the fulcrum screw-stud 86 and having the upwardly projecting arm 87 carrying a roller-stud 88 adapted to rest in contact with the end 89 of the controlling cam 17. The extremity 89 of the cam 17 affords a stop-shoulder to maintain the angle-lever 85 87 in position to hold the stop-lever 76 retracted for continuing the plunger-bar 75 disengaged from the stopping 130

cam 7, but when the notch 89' is presented to the roller-stud 88 at the completion of a rotation of the controlling cam 17, this notch affords a clearance recess which is entered by the roller-stud under the action of the spring 80 upon and through the stop-lever 76, thus permitting the plunger-bar 75 to assume a position in register with the lower part of the periphery of the cam 7 and to be forced downwardly by the same until permitted to rise into the notch 9 under the action of the spring 79.

The collar 74 is laterally retracted from the plunger-pin 70 when the stop-lever is tilted to disengage the stopping elements and throw the belt from the loose to the fast pulley, but when the stop-lever returns to stopping position, the collar 74 assumes operative relation with the plunger-pin 70 with its upper or operative face above the latter. As the plunger descends under the action of the peripheral portion of the cam 7, the pin 70 is forced inwardly by engagement with the inclined adjacent side portion 25 of the collar until the top of the latter descends beneath it, when the pin snaps out above the same, and in the ascent of the plunger-bar 75 to enter the cam-notch 9 the collar 74 forcibly engages the plunger-pin 30 70 and tilts the rock-lever 66 68 which produces a similar effect upon the rock-lever 62 63 and lifts the presser-bar and with it the presser-foot in opposition to the spring 22.

The tilting of the rock-lever arm 63 by the means just described causes the latter's forcible engagement with the roller-stud 52 of the arm 51 which causes the final step of the operative movement of the nipping and cutting blades 37 and 38, a clearance portion 40 60' being formed in the cam-groove 60 to permit the slight lateral movement of the roller-stud 59 produced by the presser-foot lifting mechanism.

As represented in Figs. 1, 2 and 7, the mechanism is in stopping position just succeeding a nipping and cutting action at the completion of a button-fastening operation. Upon the actuation of the treadle-rod 82, the stop-lever 76 is rocked to start the machine, and the presser-foot lowered upon the throat-plate 90 through the disengagement of the collar 74 with the plunger-pin 70, the treadle-rod being maintained lowered until the notch 89' has moved out of register with the roller-stud 88 when the latter is permitted to rest against the stop-member 89 to maintain the stop-lever in running position for a complete stitching cycle. The nipping and cutting elements 40 and 41 are not disturbed until the completion of the first few stitches of the cycle, after which the action of the cam-groove 60 upon the roller-stud 59 causes the rocking of the operating lever 49 51 58 to shift the operative elements 40 and 41 across the needle-path

while the needle is raised between stitches to direct the lead of the needle-thread intermediate such elements and the adjacent end of the channel or guideway 88.

During the final rotation of the main-shaft 4 in a stitching cycle, the portion 60' of the cam-groove 60 acts upon the roller-stud 59 to impart a partial retractive movement to the nipping and cutting elements so as to loosely embrace the needle-thread, as represented in Fig. 6, presenting thereafter to the roller-stud a widened portion 60' across which it is shifted by a quick movement in the final nipping and cutting stage of the operation under the action of the presser-foot lifting mechanism coincident with the arrest of the main-shaft by the stop-motion device. At the end of the stitching operation, the take-up lever 91 is preferably in its highest position, so that there will be no strain upon the nipped needle-thread at the beginning of the initial stitch of the succeeding group.

We have not described herein the button presenting means shown in the accompanying drawings, as they form the subject of a pending application filed simultaneously herewith.

Having thus set forth the nature of the invention, what we claim herein is:

1. In a sewing machine, the combination with stitch-forming mechanism, and a work-support, of a presser-foot, a thread-cutting device sustained thereby, a connection between the presser-foot and the thread-cutting device through which operative movement is imparted to the latter, a spring for lifting the presser-foot, and a cam for compressing said spring and controlling its action in lifting the presser-foot.

2. In a sewing machine, the combination with stitch-forming mechanism, and a work-support, of a presser-foot, a thread-cutting device sustained thereby, lifting means for the presser-foot comprising a spring and a cam for compressing said spring and controlling its action in lifting the presser-foot, and an operative connection between the lifting means and the thread-cutting device whereby the movement of the lifting means is transmitted to the thread-cutter.

3. In a sewing machine, the combination with stitch-forming mechanism, and a work-support, of a presser-foot formed with a transverse channel, a thread-cutting device comprising a blade slidably mounted within said channel and having an operative portion movable across the range of action of the stitch-forming mechanism, presser-foot lifting means comprising a spring and a cam for compressing said spring and controlling its action in lifting the presser-foot, and a connection between the presser-foot lifting means and said blade whereby move-

ment of the lifting means is transmitted to the thread-cutter.

4. In a sewing machine, the combination with stitch-forming mechanism, and a work-support, of a presser-foot, a thread-cutting device including a severing member, a controlling cam for determining the period of action of the stitch-forming mechanism, a connection between the controlling cam 10 and the thread-cutting device for positioning the severing member preparatory to a cutting action, presser-foot lifting means, and a connection between said lifting means and the thread-cutting device for imparting to said severing member a second movement in the same direction to cut the thread.

5. In a sewing machine, the combination with stitch-forming mechanism, and a work-support, of a presser-foot formed with 20 a transverse channel, a thread-cutting device comprising a blade slidably mounted within said channel and having an operative portion movable across the range of action of the stitch-forming mechanism, a swinging operating lever, a link having pivotal connections with said blade and lever, presser-foot lifting means, and an operative connection between said lifting means and said lever.

30 6. In a sewing machine, the combination with stitch-forming mechanism, and a work-support, of a presser-foot formed with a transverse channel, a thread-cutting device comprising a blade slidably mounted within 35 said channel and having an operative portion movable across the range of action of the stitch-forming mechanism, presser-foot lifting means, a plural-armed operating lever having one arm connected with said 40 blade, a second arm connected with and actuated by a cam, and a third arm operatively connected with the presser-foot lifting means.

7. In a sewing machine, the combination 45 with stitch-forming mechanism, of a thread-cutting device including a blade movable across the range of action of the stitch-forming mechanism, a controlling cam, a connection between said controlling cam and said blade from which the latter derives 50 successively a single retractive movement from operative position and a partial advance movement toward the same, and means timed in its action by a connection 55 with said controlling cam for imparting to said blade a further advance movement into initial operative position.

8. In a sewing machine, the combination 60 with stitch-forming mechanism, and a stop-motion including an endwise-movable plunger-bar for controlling the period of action of the same, of a thread-cutting device including a blade movable across the range of action of the stitch-forming mechanism, a 65 controlling cam, a connection between said

controlling cam and said blade whereby the latter is successively retracted from operative position and given a partial advance movement toward the same, controlling means carried by said cam for tripping the 70 stop-motion into action to arrest the stitch-forming mechanism, and means connected with and actuated by the plunger-bar of said stop-motion device for completing the advance of said knife to initial operative position. 75

9. In a sewing machine, the combination with stitch-forming mechanism, and a work-support, of a presser-foot formed with a transverse channel, a thread-cutting and nipping element slidably mounted within said channel and having an operative portion movable across the range of action of the stitch-forming mechanism and having one face formed with an indentation and adapted to act in conjunction with a wall of such channel in nipping the thread, and means for imparting operative movements to said blade. 80

10. In a sewing machine, the combination with stitch-forming mechanism including a reciprocating needle, and a work-clamping member, of a thread-cutting and nipping blade formed with a lateral extension movable across the needle-path and provided 90 with thread-cutting and -nipping edges, cutting and nipping elements disposed permanently at one side of the needle-path for co-operation with the cutting and nipping edges of the extension of said blade, a support for said blade and the co-operating cutting and nipping elements sustained by and movable toward and from the work with said work-clamping member and provided with a guideway in which said blade is 100 mounted for endwise rectilinear reciprocation, a rock-lever mounted upon a fixed fulcrum, a link connection between said rock-lever and said blade for imparting rectilinear movements to the latter, and means acting at intervals comprising a plurality of 105 stitch-forming cycles for imparting reciprocal operative movements to said blade relatively to said co-operating thread-cutting and nipping elements. 110

11. In a sewing machine, the combination with stitch-forming mechanism, of a thread-cutting and -nipping device including a longitudinally reciprocating blade formed with a lateral extension movable across the range 120 of action of the stitch-forming mechanism and having thread-cutting and -nipping edges, a support provided with a guideway in which said blade is mounted for endwise rectilinear reciprocation, cutting and nipping elements disposed permanently at one side of the stitch-forming mechanism for co-operation with the cutting and nipping edges of the extension of said blade, actuating means for imparting to said blade its 125 130

operative movements for action upon the
thread, and means acting independently of
said actuating means within a period includ-
ing at least one complete stitch-forming
cycle for imparting to said blade retractive
movements from operative relation with the
relatively fixed elements.

In testimony whereof, we have signed our

names to this specification, in the presence of
two subscribing witnesses.
